UNITED STATES PATENT OFFICE.

RAYMOND L. PLUMLEY, OF BROOKLYN, NEW YORK, ASSIGNOR TO FREDERICK OSANN COMPANY, OF NEW YORK, N. Y., A CORPORATION OF NEW YORK.

SHUTTLE OPENER.

Application filed July 31, 1923. Serial No. 654,852.

My present invention relates to rotary hook sewing machines, and the general object of the invention is to provide improved mechanism for opening the shuttle i. e. for 5 intermittently adjusting the shuttle to permit the passage of the thread between the portion of the shuttle and the stationary part normally engaging said portion to prevent the shuttle from rotating with the revolving hook in which the shuttle is mounted. My invention is characterized by the 10 fact that the shuttle opening force is applied to the shuttle in such direction and at such a point as to minimize the force required, and to minimize the required movement of 15 the shuttle and the shuttle opening mechanism.

The various features of novelty which characterize my invention are pointed out 20 with particularity in the claims annexed to and forming a part of this specification; for a better understanding of the invention however, its advantages and specific objects attained with its use, reference should be had 25 to the accompanying drawings and descriptive matter in which I have illustrated and described a preferred embodiment of my invention.

Of the drawings; 30 Fig. 1 is a side elevation of a sewing machine head with parts broken away and in section;

Fig. 2 is an end elevation of a portion of the apparatus shown in Fig. 1;

Fig. 3 is a section on the line 3—3 of 35 Fig. 2;

Fig. 4 is an elevation partly in section on the line 4—4 of Fig. 3;

Fig. 5 is a view taken similarly to Fig. 4, 40 but illustrating a different relative position of parts.

In drawings, A represents a sewing machine head, and A' the base or bed thereof. The main shaft B of the sewing machine is 45 journaled in the upper portion of the head A, and through a belt C drives the hook shaft D, which is located below the head. At the front end of the sewing machine the hook shaft D carries the ring shaped hook element E, which is provided with a hook E' proper, and with an internal bearing E² for the shuttle F. The latter is formed with a bearing rim F' received in the hook ring bearing E², and is provided with a radial 50 extension or arm F² which projects beyond

the periphery of the hook ring, and is formed with shoulders F³ and F⁴ between which extends the fixed arm or stop A², carried by the sewing machine bed and serving to prevent the shuttle F from rotating with the hook E. Sufficient clearance is provided to permit the passage of the thread between the stop A² and the projection F² in each loop forming operation. In so far as above described the sewing machine mechanism is of 60 a type well known and commonly employed in high speed power driven sewing machines, though the mechanism actually illustrated is adapted to receive a thread holding bobbin in its shuttle several times larger than is employed in high speed sewing machines now 65 in use.

In operation the frictional drag of the rotary hook E on the shuttle F tends to hold the shoulder F⁴ against the stop A². In accordance with the present invention, the shoulder F⁴ is moved away from the stop A² at the proper time in each loop forming operation, by means of a shuttle opening arm G' carried by a rock shaft G journaled under the bed A', and oscillated by means of a connecting rod H which is connected at one end to the rock shaft arm G² and at the other end is attached to an eccentric strap H' surrounding an eccentric carried by the main shaft B. The shuttle opening arm G' is shaped and disposed to engage the shuttle arm F² in front of the shoulder F³, and thereby apply a shuttle opening force to the shuttle which is substantially in line with the direction of movement of separation between the stop arms A² and the shoulder F⁴ thereby produced. Advantageously the rock shaft G is separated from the hook shaft D by a distance less than the radius of the hook ring. In consequence the rock shaft G lies back of the hook ring, and the arm G' is shaped to extend up alongside and then over the hook ring, terminating in a portion engaging the shuttle arm F², and extending away from the latter in a direction generally tangential to the hook ring.

The shuttle F fits loosely in the ring bearing E², and when the shuttle opening force is applied at the point and in the direction described, the shuttle tends to rock or roll along the lower portion of the bearing E² on which the weight of the shuttle is carried, as the shoulder F⁴ moves away from the stop A². In consequence of its described 105 110 115

character, the extent of the movement of the shuttle and the shuttle opening mechanism, required to effect a given separation between the stop A² and the shoulder F⁴, is less than with the arrangements heretofore employed in which the shuttle opener has engaged the shuttle at some point around the periphery of the latter at some distance from the stop engaging portion thereof, and has exerted its shuttle opening force in a direction at an angle to the direction of the desired movement of separation between the stop and stop engaging portion of the shuttle. As compared with shuttle opening arrangements heretofore used, the present invention is also characterized by the avoidance of chatter and by the fact that the shuttle opening movement is opposed but little, if any, by the action of gravity. The invention is especially adapted for use in a high speed sewing machine in which the shuttle is relatively large.

In the machine shown, as is usual in high speed rotary hook machines, the hook makes two revolutions for each loop forming operation, and the shuttle opening rock shaft G therefore makes one complete oscillation for each two revolutions of the hook shaft D.

It will be apparent to those skilled in the art that changes may be made in the form of the apparatus disclosed without departing from the spirit of my invention as set forth in the appended claims.

Having now described my invention, what I claim as new, and desire to secure by Letters Patent, is—

1. In a rotary hook sewing machine comprising a shuttle stop, a hook member revolving about a horizontal axis, and a shuttle mounted therein and having a portion engaging said stop to thereby prevent said shuttle from rotating with the hook member, the improvement which consists in a shuttle opening mechanism intermittently engaging the shuttle substantially in line with the resultant movement of separation between said stop and the shuttle portion engaging it.

2. In a rotary hook sewing machine comprising a shuttle stop, a hook member re-

volving about a horizontal axis, and a shuttle mounted therein and having an upper portion normally engaging said stop to thereby prevent said shuttle from rotating with the hook member, the improvement which consists in a shuttle opening mechanism intermittently engaging the shuttle and applying a force thereto at a point substantially in line with, and parallel in direction to the resultant movement of separation between said stop and the portion of the shuttle normally engaging the latter.

3. In a rotary hook sewing machine comprising a shuttle stop, a hook member revolving about a horizontal axis, and a shuttle mounted therein and formed with two spaced apart upwardly extending shoulder parts, one in front and the other in the rear of said stop, having reference to the direction of rotation of said hook member, between which said stop is loosely received to thereby restrict angular movement of the shuttle, the improved shuttle opening mechanism comprising a rock shaft oscillating about an axis parallel to the axis of the hook member and provided with an arm engaging the front shoulder part and moving the latter toward the stop as said shaft is oscillated.

4. In a rotary hook sewing machine comprising a main shaft, a shuttle stop, a hook member revolving about a horizontal axis, driven from said shaft and a shuttle mounted therein and formed with an upwardly extending shoulder part normally engaging the rear side of said stop having reference to the direction of rotation of said hook member, to thereby restrict angular movement of the shuttle, the improved shuttle opening mechanism comprising a rock shaft oscillating about an axis parallel to the axis of the hook member by said main shaft, and provided with a bent arm extending over said hook member and engaging said shoulder part to move the latter away from said stop.

Signed at New York city, in the county of New York and State of New York this 27 day of July, A. D. 1923.

RAYMOND L. PLUMLEY.
